United States Patent Office

Des. 225,188
Patented Nov. 28, 1972

225,188

OVERSHOE

Mary Keeney Iskyan, 34—15 74th St.,
Jackson Heights, N.Y. 11372

Filed Sept. 4, 1970, Ser. No. 24,834

Term of patent 14 years

Int. Cl. D2—04

U.S. Cl. D2—279

Fig. 1

Fig. 2

FIG. 1 is a side perspective view of an overshoe showing my new design; and

FIG. 2 is a rear elevational view thereof.

I claim:

The ornamental design for an overshoe, substantially as shown.
